CRATE

Merton V. Albaugh, Berwyn, Ill.

Application September 6, 1932, Serial No. 631,822

2 Claims. (Cl. 217—36)

The present invention relates generally to crates for use in transporting and vending vegetables and other farm produce. More particularly, the invention relates to that type of crate which is formed for the most part of wooden slats, and comprises a pair of sides, a pair of ends and a bottom.

One object of the invention is to provide a transporting and vending crate of this type which is more durable and rigid than previously designed crates for the same purpose and may be shipped by the manufacturer to the user in knock-down form and assembled quickly and readily by the user.

Another object of the invention is to provide a crate of the type under consideration in which the sides and ends are secured fixedly together by means of four elongated, upstanding corner-brackets which are formed of steel or any other suitable metal and are bent longitudinally and at right angles so as to form legs for lapping and supporting the ends of the slats.

Another object of the invention is to provide a crate of the last mentioned character in which the legs of the four metallic corner-brackets embody inwardly extending prongs for penetration within the ends of the slats and have oppositely facing pairs of tongues which are adapted to be bent around the slat-ends and serve to hold the slats against vertical displacement and in connected relation with respect to the inwardly extending prongs.

A further object of the invention is to provide a transporting and vending crate of the character and type under consideration which comprises in addition to the four upstanding corner-brackets, a pair of horizontally extending tongue-equipped brackets which serve to connect in place the ends of the bottom slats and are connected to the lower ends of the corner brackets so as to effect a rigid connection between the bottom and the sides and ends of the crate.

A still further object of the invention is to provide a crate of the aforementioned type in which each of the horizontally extending brackets for securing in place the bottom slats has the ends thereof connected pivotally to the lower ends of two of the upstanding corner-brackets so that such two corner-brackets may be swung together for shipping purposes.

In addition, it is contemplated as one of the objects of the invention to provide a transporting and vending crate which is generally of new and improved construction and may be manufactured at a low and reasonable cost.

Other objects of the invention and the various advantages and characteristics of the present crate construction will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective of a crate embodying the invention;

Figure 2 is a fragmentary perspective of one of the corners of the crate, showing in detail the manner in which the prongs and tongues of the corner-brackets and horizontally extending brackets serve to connect fixedly in place the ends of the slats which form the sides, ends and bottom of the crate;

Figure 3 is a detailed horizontal section exhibiting the manner in which the ends of the slats which form the sides and ends of the crate are secured and held fixedly in abutting relation by the corner-brackets;

Figure 4 is a vertical section of the portion of the crate which is shown in Figure 3; and

Figure 5 is a perspective of one of the horizontally extending brackets for securing in place the bottom slats, showing the manner in which such bracket is connected pivotally to the lower ends of two of the corner-brackets so that the latter may be swung together into substantially parallel relation for shipping purposes.

The crate which forms the subject matter of the present invention is designed primarily to be used by truck farmers in connection with the transportation and vending of vegetables and other farm produce. It is rectangular in conformation and comprises a pair of sides 6, a pair of ends 7 and a bottom 8. Each of the sides consists of four horizontally extending, vertically spaced, wooden slats 9. Each of the ends 7 consists of four wooden slats 10. The latter extend horizontally and are spaced apart vertically. The bottom 8 consists of four horizontally extending, laterally spaced, wooden slats 11. In addition to the sides, ends and bottom, the crate comprises four elongated, upstanding corner-brackets 12 and two horizontally extending brackets 13. The upstanding corner brackets 12 serve to hold in place the slats of the sides and ends of the crate and are connected directly to the ends of the slats 9 and 10.

as described hereafter. The horizontally extending brackets 13 serve to hold in place the slats 11 of the bottom and operate to effect a rigid connection between the bottom and the sides and ends of the crate.

The upstanding corner-brackets 12 are formed of steel or any other suitable metal and are bent longitudinally so as to form legs 14 and 15 which extend at right angles to each other. The brackets are preferably bent so that the legs 15 are slightly wider than the legs 14. The ends of the side slats 9 fit against the inner faces of the legs 14 and are arranged so that the end edges thereof abut directly against the inner faces of the legs 15, as shown particularly in Figure 3 of the drawing. In order to hold the ends of the side slats 9 in place, the legs 14 of the corner-brackets 12 are provided with V-shaped prongs 16. These prongs are formed integrally with and extend inwardly from the free edges of the legs 14 and are embedded in the ends of the side slats by driving the latter thereagainst. In order to prevent the slats from being loosened with respect to the prongs and to hold the slats against vertical displacement, pairs of tongues 17 are provided. These tongues are formed integrally with extension parts 18 on the free edges of the legs 14 and between the prongs 16. The tongues of each pair face one another and are bent inwardly with respect to the extension parts 18 in such a manner that they lap and contact directly with the side edges of the slats 9. The extreme distal ends of the tongues are bent at right angles to the portions which lap the side edges of the slats 9 and fit against the inner faces of the slats 9, as shown in Figure 2, in order to lock the slats against inward displacement to prevent them from becoming loose relatively to the prongs. The extension parts 18 serve to space the tongues 17 from the free side edges of the legs 14. The upper tongues of the uppermost pairs, instead of being connected to the extension parts, are formed as extensions of the upper ends of the corner-brackets 12 (see Figure 2). The ends of the end slats 10 fit against the inner faces of the legs 15 and are arranged so that the end edges thereof abut directly against the ends of the side slats 9 as shown in Figure 3. For the purpose of holding the ends of the end slats 10 in place, the legs 15 of the corner-brackets 12 are provided with V-shaped prongs 19. These prongs are formed integrally with, and extend inwardly from, the free edges of the bracket legs 15 and are embedded in the ends of the end slats 10 by hammering or driving the latter against the sides of the legs 15 onto the prongs. The prongs 19 are horizontally aligned with the prongs 16 and serve to hold the slats 10 of the ends 7 of the crate in alignment with the slats 9 of the sides 6. In order to hold the slats 10 against vertical displacement and to prevent them from being loosened with respect to the prongs 19, pairs of oppositely facing tongues 20 are provided. These tongues are formed integrally with extension parts 21 on the free or outer edges of the bracket legs 15 and are bent inwardly so that they lap the side edges of the slats 10. The outer or distal ends of the tongues 17 are bent at right angles to the portions which lap the side edges of the slats 10 and fit directly against the inner faces of the slats 10 so as to prevent inward movement of the slats. The tongues 20 are spaced from the outer or free

edges of the legs 15 by the extension parts 21 and are horizontally aligned with the tongues 17 on the bracket legs 14. The extension parts 21 are positioned between the prongs 19 and each embodies the lower tongue of one pair and the upper tongue of the subjacent pair. The upper tongues 20 of the uppermost pairs are in the nature of extensions of the upper ends of the bracket legs 15 instead of being attached to the extension parts. An advantage and characteristic of utilizing the prongs and tongues on the legs 14 and 15 of the corner-brackets 12 is that the slats of the sides and ends of the crate are secured rigidly together. An additional advantage and characteristic of utilizing the prongs and tongues is that no nails need be used in the fabrication of the crate and the crate is extremely durable and well adapted for the purpose for which it is designed.

The horizontally extending brackets 13 are formed of steel like the corner-brackets 12, and are bent longitudinally so as to form vertically extending legs 22 and horizontally extending legs 23. They are positioned directly beneath the slats 10 of the crate-ends 7 and are connected by rivets 24 to the legs 15 of the corner brackets 12. The ends of the slats 11 of the bottom 8 rest upon the horizontally extending legs 23 of the brackets 8 and are arranged so that the end edges thereof abut directly against the inner faces of the vertically extending legs 22. Oppositely facing pairs of tongues 25 are associated with the horizontally extending legs 23 and serve to hold the bottom slats 11 in place. The tongues 25 are formed integrally with extension parts 26 on the outer or free edges of the legs 23 and are bent upwardly and then inwardly so as to lap the side edges of the slats 11 and fit against the top faces of the slats so as to prevent vertical and horizontal displacement of the slats with respect to the bracket legs 23.

The crate is preferably shipped from the manufacturer to the user in knock-down form, that is, with the slats separate from the corner brackets 12 and the horizontally extending brackets 13. In order to facilitate shipment of the brackets, the prongs and tongues are not bent into place and the rivets 24 are arranged so that they extend through the ends of the vertically extending legs 22 of the brackets 13 and permit the corner-brackets to swing together into substantially parallel relation, as shown in Figure 5. The two corner-brackets for each horizontally extending bracket 13 are preferably arranged so that one pivots against the inner face of the vertically extending leg 22 and the other pivots against the outer face of said leg. This arrangement facilitates swinging the corner-brackets into shipping position.

In assembling the crate, the corner-brackets 12 are first swung into their normal or operative position and then the prongs and tongues on the legs 14 and 15 are bent at right angles to the legs by the use of pliers or any other suitable tool. After bending of the prongs and tongues on the legs of the corner-brackets 12, the tongues 25 on the horizontally extending legs 23 of the brackets 13 are bent upwardly, as shown in Figure 2. Upon completion of the prong and tongue bending operation, the bottom slats 11 are arranged so that the ends thereof fit between the tongues 25 and rest on the legs 23. While the bottom slats are in this position, the tongues 25 are driven over the top faces of the bottom slats in order to secure the bottom slats in con-

nected relation with respect to the brackets 13. After assembly of the bottom of the crate, the side slats 9 are positioned so that the ends thereof fit between the tongues 17. While in this position, the slats are hammered outwardly in order to embed the prongs 16 into the slats. After the driving or hammering operation, the tongues 17 are bent over the inner faces of the side slats 9 in order to form locking connections whereby the slats are held against vertical and inward displacement. After the sides of the crate are in place, the end slats 10 are arranged so that the ends thereof fit between the tongues 20 of the legs 15 of the corner-brackets. While so positioned, the slats are driven outwardly in order to embed the prongs 19 into the ends of the end slats. With the prongs so embedded, the outer or distal ends of the tongues 20 are bent over the inner faces of the end slats 10, as shown in Figure 2. This last operation completes the assembly of the crate. In its assembled or completed form, the crate is extremely durable, is capable of withstanding rough usage by reason of the fact that the slats which form the bottom, sides and ends are permanently and efficiently locked in place.

The crate herein described may be manufactured at a low and reasonable cost and may be sent from the manufacturer to the user in knock-down form.

Whereas the crate has been described as being adapted primarily for use in transporting and vending vegetables and other farm produce, it is to be understood that the crate may be put to other uses. It is also to be understood that the invention is not to be restricted to the details set forth, since these may be modified within the scope of the appended claims, without departing from the spirit and scope of the invention.

Having thus described the invention, what I claim as new and desire to secure by Letters Patent, is:

1. A crate comprising in combination, a polygonal bottom, elongated, upstanding, metallic corner-brackets at the corners of the bottom bent longitudinally to form angularly disposed legs and having prongs on the legs and oppositely facing pairs of tongues at opposite sides of the prongs and on the legs, and horizontally extending, side-forming slats arranged in vertical series between the corner-brackets and having the ends thereof arranged so that they fit between the tongues and have the prongs embedded therein, the outer ends of the tongues being bent around the side edges of the slats so as to secure the slats in place and hold them against displacement with respect to the prongs.

2. A crate comprising in combination, a polygonal bottom, elongated, upstanding, metallic corner-brackets at the corners of the bottom bent longitudinally to form angularly disposed legs and having on the free or outer edges of the legs inwardly extending V-shaped prongs and oppositely facing, inwardly extending pairs of tongues at the sides of the prongs, and horizontally extending, side-forming slats arranged in a vertical series between the corner-brackets and having the ends thereof arranged so that they fit against the inner faces of the legs and between the tongues and having the prongs embedded therein, said tongues being longer than the slats are thick and having the outer ends thereof bent around the side edges of the slats and over the inner faces of the slats so as to secure the slats in place and prevent them from being displaced with respect to the prongs.

MERTON V. ALBAUGH.
